UNITED STATES PATENT OFFICE.

LEVI PENTZ, OF CANTON, OHIO, ASSIGNOR OF ONE-HALF TO MICHAEL W. OBERLIN, OF SAME PLACE.

WASHING-MACHINE.

SPECIFICATION forming part of Letters Patent No. 357,966, dated February 15, 1887.

Application filed September 8, 1886. Serial No. 212,970. (No model.)

To all whom it may concern:

Be it known that I, LEVI PENTZ, a citizen of the United States, residing at Canton, in the county of Stark and State of Ohio, have invented certain new and useful Improvements in Washing-Machines; and I do hereby declare that the following is a full, clear, and exact description of the same, reference being had to the annexed drawings, making a part of this specification, and to the letters and figures of reference marked thereon, in which—

Figure 1 is a perspective view showing machine attached to a wash-board and in position for use. Fig. 2 is a perspective view showing wash-board detached.

The present invention has relation to washing-machines; and its nature consists in the different parts and combination of parts hereinafter described, and particularly pointed out in the claim.

Similar letters of reference indicate corresponding parts in each figure of the drawings.

In the accompanying drawings, A represents the wash-board, which may be of any desired kind, and may be made in the ordinary manner. To the side pieces or back of the wash-board A is securely attached the bar B by means of suitable screws or their equivalents. To the ends of the bar B are securely attached the posts or standards C C, said posts or standards being substantially of the form shown in the drawings, and, as shown, their top or upper ends are provided with the balls D D. Said balls may be formed integral with the posts or standards C C, or they may be made separate and attached in any convenient manner. The balls or heads D D are provided with the apertures a, which are for the purpose of receiving the pins b, as shown in the drawings. The pins b are provided with the balls or heads E, said balls or heads being provided with the apertures e, which are for the purpose of guiding and holding the arms F. To the bottom or lower ends of the arms F is securely attached the cross bar G, which may be substantially of the form shown in the drawings. The bottom or under side of the

cross-bar G is provided with the semicircular block H, which is substantially of the form shown in the drawings. This semicircular block H may be formed integral with the cross-bar G, or it may be made separate and attached in any well-known manner. The rubbing-surface of the semicircular block H is properly covered with the rubber covering I, said covering being provided with the grooves J, said grooves extending diagonally across the surface, as shown in Fig. 2. The object and purpose of having the grooves extend diagonally across the covering I is to provide a better rubbing-surface by throwing the ribs of a wash-board out of line, thereby providing an angular pressure upon the clothing, and better removing the dirt therefrom. The handle K is located substantially as shown, and is for the purpose of operating the machine.

For the purpose of holding the different parts in proper position the spring-keys J' are provided, which are located substantially as shown in the drawings.

Having now fully described my invention, what I claim as new, and desire to secure by Letters Patent, is—

The combination, with a common wash-board, A, having attached thereto the bar B, of the posts or standards C C, provided with the heads or balls D D, the pins b, provided with the heads or balls E, said heads or balls E being provided with the apertures e, the arms F, passing through the apertures e, the cross-bar G, provided with the semicircular block H, and having its rubbing-surface covered with rubber or like elastic material, having diagonal grooves J, and the handle K, all arranged substantially as described, and for the purpose specified.

In testimony that I claim the above I have hereunto subscribed my name in the presence of two witnesses.

LEVI PENTZ.
